CLAIM

The ornamental design for a bubble machine toy as shown and described.

DESCRIPTION

FIG. 1 is a front and top perspective view showing of a bubble machine toy showing my new design;

FIG. 2 is a rear and top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view of a portion indicated with numeric 9 in FIG. 1;

FIG. 10 is an enlarged partial view of a portion indicated with numeric 10 in FIG. 1;

FIG. 11 is an enlarged partial view of a portion indicated with numeric 11 in FIG. 1;

FIG. 12 is an enlarged partial view of a portion indicated with numeric 12 in FIG. 1;

FIG. 13 is an enlarged partial view of a portion indicated with numeric 13 in FIG. 3;

FIG. 14 is an enlarged partial view of a portion indicated with numeric 14 in FIG. 5;

FIG. 15 is an enlarged partial view of a portion indicated with numeric 15 in FIG. 6; and,

FIG. 16 is an enlarged partial view of a portion indicated with numeric 16 in FIG. 8.

The broken lines in the figures illustrate portions of the bubble machine toy that form no part of the claimed design, and the dash-dot-dash lines shown in the drawings are for the purpose of showing the area of enlargement and form no part of the claimed design.

1 Claim, 16 Drawing Sheets
